UNITED STATES PATENT OFFICE

ALEXANDER R. G. HORNE, OF TORONTO, ONTARIO, CANADA

FEED GAUGE FOR PRINTING PRESSES

Application filed May 26, 1930. Serial No. 455,779.

This invention relates to sheet gauges or guides for platen printing presses and which are attached to the tympan or sheet drawn over the platen. Various gauges for this purpose have been devised, one type being that in which the gauge is cemented or glued to the surface of the tympan sheet. The use of the cement or glue is messy, and it is difficult to make the device stick in place, and it often results in a tearing of the sheet, making its replacement necessary. Another common type is that provided with a prong which is inserted through a hole in the tympan sheet. This form is difficult to maintain in place on account of the liability of the tympan sheet to tear, and further most of this type results in an objectionable bulge in the tympan sheet which further increases the liability to tear.

My object is to devise a construction which will avoid the use of glue or other adhesive and with which the likelihood of tearing the sheet is reduced.

I attain my object by providing a base member which is inserted beneath the tympan sheet and a guide member which is placed above the tympan sheet to clamp the sheet between them, these members being provided with co-acting teeth or engaging members which are adapted to pass through holes in the sheet. The construction is hereinafter more fully described and illustrated in the accompanying drawings in which

Fig. 1 is a perspective view of my improved gauge attached to a tympan sheet;

Fig. 2 a longitudinal section through the gauge, the base and guide being in separated relationship;

Fig. 3 a plan view of the gauge;

Fig. 4 a perspective view showing the method of separating the guide from the base;

Fig. 5 a plan view of a modified form of gauge;

Fig. 6 a plan view of another modified form; and

Fig. 7 a section on the line 7-7 in Fig. 6.

In the drawings, like numerals of reference indicate corresponding parts in the different figures.

1 indicates the tympan sheet to which the gauge is to be applied. The gauge comprises a base member A and a guide member B. The base member is formed as a flat plate 2 having adjacent one end a pair of spaced teeth 3 bent up at one end and adjacent its other end a pair of holes 4. Teeth 5 may be formed on the under side of the plate 2 to prevent slipping of the plate. The upper ends of the teeth 3 are sufficiently sharp to pierce the material of the tympan sheet.

The guide member B is also formed from a sheet of flat metal 6 having longitudinal slits 7 formed therein. The ends of the outer parts are shaped to form tongues 8 adapted to engage with the teeth 3, said teeth being notched at 9 to receive the edge of the tongue. The tongues 8 are also notched at 10 to receive the sides of the teeth 3. It will be noted that the outer edge of at least one of the tongues 8 is curved for a purpose which will hereinafter appear. The guide 6 is preferably provided with projections 21 on its lower side adapted to engage in the holes 4 in the base.

Slidably mounted on the guide plate 6 is a stop member 11 which is carried by a screw 12 threaded through a hole in a lug 13 secured to the upper side of the plate 6.

The gauge is placed in position as follows: The base member A is placed beneath the tympan sheet with its teeth 3 projecting through to the upper side thereof. The guide member B is then placed in position with the notches 10 in the sides of the tongues 8 in interlocking engagement with the notches in the sides of the teeth 3. The rear end of the guide plate 6 is then forced downwardly to cause the projections 21 in its under side to pierce the tympan sheet and enter the holes 4 in the base. The stop 11, or guide member proper, may then be adjusted as desired.

To remove the gauge, it is simply necessary to lift the rear end of the plate 6 to disengage the projections 21 from the holes 4 and tympan sheet, and, using one pair of engaging notches 9 and 10 as a pivot, rock the upper plate 6 relative to the lower, as indicated by the arrow in Fig. 4, to disengage

the opposite pair, which thus allows complete separation of the parts.

In Fig. 5 I show a modified form in which the guide plate is provided with a screw 14 having a vertical axis. Slidable on the plate 6 is a stop member 15 having a slot 16 formed therein through which the screw 14 projects. A clamping nut 17 is provided on the screw 14 for clamping the stop member in position 10 as adjusted.

In Figs. 6 and 7 another modification is shown. In this construction the lugs 18 and 19 which support the adjusting screw are formed by bending up tongues from the flat 15 sheet of which the device is formed. Two additional tongues 20 are bent up at the forward end of the guide member which are notched to receive the edges of the stop or 20 guide proper 11 and maintain the latter in position. These tongues 20 also co-act with the teeth 3 to position the guide relative to the base.

From the above description it will be seen that I have devised a construction which will 25 satisfactorily attain the object of my invention as set out in the preamble of this specification.

What I claim as my invention is:

1. In a feed gauge for printing presses, the 30 combination of a base member adapted to be positioned entirely below a tympan sheet and a guide member adapted to be positioned above the sheet, one of said members having sheet piercing projections thereon adapted to be interengaged with the other member, to prevent separation of said members in a plane normal to the surface of the sheet.

2. In a feed gauge for printing presses, the 35 combination of a base member adapted to be positioned below a tympan sheet and a guide member adapted to be positioned above the sheet, said base member having teeth thereon adapted to pierce the sheet, said guide member being adapted to be releasably engaged with said teeth to clamp the sheet between the members.

3. In a feed gauge for printing presses, the 40 combination of a base member adapted to be positioned below a tympan sheet and a guide member adapted to be positioned above the sheet, said base member having teeth thereon adapted to pierce the sheet, and tongues on said guide member adapted to be releasably engaged with said teeth to clamp the members together.

4. In a feed gauge for printing presses, the 45 combination of a base member adapted to be positioned below a tympan sheet and a guide member adapted to be positioned above the sheet, said base member having teeth thereon adjacent one end adapted to pierce the sheet and a hole adjacent its other end; and tongues on said guide member adapted to be 50 releasably engaged with said teeth, and a pro-

jection on its lower side adapted to enter the hole in the base.

5. In a feed gauge for printing presses, the 55 combination of a base member adapted to be positioned below a tympan sheet and a guide member adapted to be positioned above the sheet, one of said members having sheet piercing projections thereon adapted to be interengaged with the other member; and an adjustable stop carried by said guide member.

6. In a feed gauge for printing presses, the 60 combination of a base member adapted to be positioned below a tympan sheet and a guide member adapted to be positioned above the sheet, said base member having teeth thereon adapted to pierce the sheet, said guide member being adapted to be releasably engaged with said teeth to clamp the sheet between the members; and an adjustable stop carried by said guide member.

7. In a feed gauge for printing presses, the 65 combination of a base member adapted to be positioned below a tympan sheet and a guide member adapted to be positioned above the sheet, said base member having teeth thereon adapted to pierce the sheet, said teeth each having a notch formed in its side; and tongues on said guide members adapted to be releasably engaged in said notches.

8. For use with a tympan sheet, a feed 70 gauge comprising a base member adapted to be located entirely below said sheet and having teeth on its upper surface adapted to be projected through said sheet; and a guide member adapted to be positioned above the sheet engaged with said teeth, to prevent separation of said members in a plane normal to the surface of the sheet.

Signed at Toronto, Canada, this 15th day 75 of May, 1930.

ALEXANDER R. G. HORNE.
